United States Patent Office.

JOHN MAGEE, OF CHELSEA, MASSACHUSETTS, ASSIGNOR TO THE MAGEE FURNACE COMPANY.

Letters Patent No. 78,217, dated May 26, 1868.

IMPROVEMENT IN COOKING-STOVES.

The Schedule referred to in these Letters Patent and making part of the same.

TO ALL WHOM IT MAY CONCERN:

Be it known that I, JOHN MAGEE, of Chelsea, in the county of Suffolk, and State of Massachusetts, have invented certain Improvements in Cooking-Stoves, of which the following is a full, clear, and exact description, reference being had to the accompanying drawings, making part of this specification, in which—

Figure 1 is a perspective view of a cooking-stove with my improvements applied thereto.

Figure 2 is a longitudinal vertical section through the centre of the same.

Figure 3 is a transverse vertical section on the line $x-x$ of fig. 2.

Figure 4 is a horizontal section on the line $y-y$ of fig. 2, a portion of one of the parts being broken away to better illustrate my improved flue.

Figure 5 is a plan of the bottom of a cooking-stove having my improved flue applied thereto.

My present invention is briefly referred to in two other applications for Letters Patent of the United States, made by me simultaneously with this; and my invention consists in an auxiliary flue placed at the bottom of the stove, underneath the return flue of the oven, the office of the said auxiliary flue being to collect and economize the heat which radiates from the bottom of stoves of the ordinary construction, and to create a current of air for conducting said economized heat into the oven, by which construction I am enabled to increase the volume of hot air to intensify the heat of and ventilate the oven, and also to supply air for the consumption of the gases arising from the fuel in the fire-box.

To enable others skilled in the art to understand and use my invention, I will proceed to describe the manner in which I have carried it out.

In the said drawings, A represents the top-plate of a cooking-stove. B is the fire-box, provided with a swinging grate, a , at its bottom, and a stationary or removable grate, b , at its front. C is a roasting-closet, placed in front of the grate b , which is open, to allow the direct rays of heat to be conveyed therein. This roasting-closet C is provided with a swinging lid, D, and has a warming-closet, E, placed directly under it, the top of the warming-closet occupying the same position as that of the hearth in an ordinary high-hearth stove.

F is a lid, hinged or otherwise secured, or made removable, and forms the bottom of the warming-closet. The details of the construction of both the roasting and warming-closets being fully set forth in one or both of separate applications made simultaneously with this, a repetition thereof is deemed unnecessary here.

I is the oven, J its direct flue, and K its return flue, the bottom of which forms the bottom proper of the stove as ordinarily constructed. L is an auxiliary flue or chamber formed between two plates, c d , placed below the bottom of the ordinary stove, underneath the return flue K, the lower plate d being provided with a series of perforations, e , or openings, to admit the air of the apartment, which then unites with and conducts the heat which radiates from the bottom of the return flue upon the upper plate c into the chamber or auxiliary flue L. The volume of hot air thus increased is then conducted by two upright tubes or pipes M into a trunk or chamber, N, extending transversely across the bottom of the back corner of the oven I, and thence through perforations f into and across the oven, and through perforations g h , formed in the bottom and top of another trunk or chamber O; at which point the current of air impinges upon the top of the ignited fuel in the fire-box, and consumes the gases arising therefrom.

To provide against the possibility of any heat passing down through the bottom plate d of the auxiliary flue L, I cover the upper side of the said plate with a layer of cement, plaster of Paris, or other non-conducting material.

By the construction above described, the heat which would otherwise be radiated from the bottom of the stove and escape into the apartment, is now not only utilized in affording additional heat to the oven, but serves to perfectly ventilate the same, and also supplies a current of air necessary for the consumption of the gases in the fire.

Either one or both the trunks or chambers N O may be dispensed with, and the air from the auxiliary flue

be introduced by one or more tubes or other conductors directly through a single perforated plate at the top and bottom corners, or at the top corner only, of the oven, without departing from the spirit of my invention.

Claim.

What I claim as my invention, and desire to secure by Letters Patent, is—

The auxiliary flue L placed below the bottom of the return flue K, and provided with suitable perforations or openings, e, in combination with one or more tubes or conductors M, and one or more perforated trunks N O, or perforated plates, substantially as and for the purpose described.

JOHN MAGEE.
